H. K. SANDELL

FINGERING DEVICE FOR STRINGED INSTRUMENTS

Filed July 15, 1922

Inventor:
Henry K. Sandell,
By C. W. Smith, Chas. Miles,
Attest.

UNITED STATES PATENT OFFICE.

HENRY K. SANDELL, OF CHICAGO, ILLINOIS, ASSIGNOR TO MILLS NOVELTY COMPANY, OF CHICAGO, ILLINOIS, A CORPORATION OF ILLINOIS.

FINGERING DEVICE FOR STRINGED INSTRUMENTS.

Application filed July 15, 1922. Serial No. 575,194.

To all whom it may concern:

Be it known that I, HENRY K. SANDELL, a citizen of the United States, residing at Chicago, in the county of Cook and State of Illinois, have invented a new and useful Improvement in Fingering Devices for Stringed Instruments, of which the following is a specification.

The present invention relates to improvements in fingering devices for self-playing stringed instruments of the violin class and particularly for such instruments of the type described in my prior Patent No. 1,094,819, dated April 28, 1914, and will be fully understood from the following description, illustrated by the accompanying drawings, in which a device embodying the invention is illustrated.

In the drawings—

Figure 1 is a sectional view showing a group of the fingering devices constructed in accordance with the present invention in elevation; and Figure 2 is a broken sectional view showing a group of the fingering devices of Figure 1 in plan.

Referring more particularly to the drawings, the numeral 10 indicates the neck of a stringed instrument, which may suitably be a violin, above which are the strings 11. A fulcrum bar 12, in which is formed a tapered fulcrum portion 13, extends along the side of the neck of the instrument substantially parallel to the strings. On the fulcrum portion 13 of this bar are mounted side by side a series of fingering levers 14, of which one is provided for each note or half note on each string above the open string note. The fingering levers 14 are each provided with a fulcrum notch 15 which rests upon the fulcrum portion 13 of the bar 12. Each fingering lever is also provided with an arm 16 extending in the direction of the strings of the instrument and suitably formed to extend under and to the corresponding string of the violin. The arms 16 of the fingering levers are provided with heads 17 in which are formed fingering notches 18 which engage the corresponding strings, these notches being suitably formed as disclosed in my Patent No. 1,381,508, dated June 14, 1921.

Each of the fingering levers 14 is provided with an arm 19 which extends from the fulcrum bar 12 opposite to the arm 16 of the corresponding lever. The arms 19 terminate each in a downwardly projecting member 20

to which is secured the end of a coil spring 21, the other end of which is secured to the device for actuating the fingering lever, which in the form illustrated is shown as the core 22 of an alternating current electro-magnet 23. Any other suitable device for actuating the fingering lever may be employed, for example, the armature of a direct current electro-magnet or a suitable mechanical device.

On each side of the fulcrum bar 12 and substantially parallel to it extend slotted bars 24, the slots of which serve as guides for the movement of the arms of the fingering levers. Suitable means for returning the fingering levers to inactive position are provided. In the form shown, an arm 25 extends forwardly and upwardly from each fingering lever on the same side of the fulcrum as the arm 16 and from the end of each arm 25 a coil spring 26 extends to a bar 27, which in the form of construction shown is secured to the forward guide-bar 24. The felted bars 28 above the arms 19 serve as stops for their upward movement. A bar 29 extends parallel to the fulcrum bar 12 slightly above the fingering levers to prevent their disengagement from the fulcrum bar.

In the operation of the fingering devices of the present invention, it is apparent that the coil springs 21 determine the force with which the strings of the instrument are engaged and that this force is substantially constant regardless of the position of the string. The present construction is particularly advantageous in connection with the playing of trills, in which a fingering lever is held against one end of the string and the fingering lever playing the next higher note or half note on the same string is rapidly engaged and disengaged. The engagement of the first fingering lever raises the string somewhat and by the present form of construction the second fingering lever is caused to engage the string with the proper force, regardless of its displaced position.

Although the present invention has been described in connection with the details of a specific device for carrying it into effect, it is not intended that these details shall be regarded as limitations upon the scope of the invention, except in so far as included in the accompanying claims.

I claim:

1. A fingering device for self-playing

string instruments, comprising a lever having a string-engaging notch in its headed end and fulcrumed to extend said notched head beneath the string, and means for actuating the lever having a resilient connection therewith.

2. A fingering device for self-playing string instruments, comprising a lever having a string-engaging notch in its headed end and fulcrumed between its ends to extend said notched end beneath the string, and lever-actuating means having a resilient connection with the rear end of the lever.

3. A fingering device for self-playing string instruments, comprising a lever fulcrumed between its ends and spring held on its fulcrum, said lever having a string-engaging notch in its headed end extending beneath the string, a slotted bar for guiding

the lever-movements, and lever-actuating means having a resilient connection with the rear end of the lever.

4. A fingering device for self-playing string instruments, comprising a lever having a string-engaging notch in its headed end and fulcrumed to extend said notched head beneath the string, means for actuating the lever having a resilient connection therewith, and stops over the lever limiting the rise thereof.

5. A fingering device for self-playing string instruments, comprising a lever having a string-engaging notch in its headed end and fulcrumed to extend said notched head beneath the string, and an electromagnet having its armature spring-connected with the opposite lever-end.

HENRY K. SANDELL.
